CLAIM

The ornamental design for a surface pattern applied to a bottle as shown and described.

DESCRIPTION

FIG. 1 is a perspective view of a surface pattern applied to a bottle, showing a first embodiment in accordance with our new design;

FIG. 2 is a left side view thereof;

FIG. 3 is a right side view thereof;

FIG. 4 is a front elevational view thereof;

FIG. 5 is a back elevational view thereof;

FIG. 6 is a top view thereof;

FIG. 7 is a bottom view thereof;

FIG. 8 is a perspective view of a surface pattern applied to a bottle, showing a second embodiment in accordance with our new design;

FIG. 9 is a left side view thereof;

FIG. 10 is a right side view thereof;

FIG. 11 is a front elevational view thereof;

FIG. 12 is a back elevational view thereof;

FIG. 13 is a top view thereof; and,

FIG. 14 is a bottom view thereof.

The bottle is shown in dash-dash broken lines for illustrative purposes only and forms no part of the claimed design.

1 Claim, 12 Drawing Sheets
